UNITED STATES PATENT OFFICE

BENJAMIN J. BUCKMAN, OF GARDNER, MASSACHUSETTS, ASSIGNOR TO
HEYWOOD BROTHERS & CO., OF SAME PLACE.

CHAIR-SEAT.

SPECIFICATION forming part of Letters Patent No. 373,582, dated November 22, 1887.

Application filed July 11, 1887. Serial No. 243,933. (No model.)

To all whom it may concern:

Be it known that I, BENJAMIN J. BUCKMAN, of Gardner, in the county of Worcester and State of Massachusetts, have invented a new and useful Improvement in Chair-Seats, of which the following is a specification, reference being had to the accompanying drawings, in which--

Figure 1 is a plan of a chair-seat embodying my invention, with its back-frame in section on line 1 1 of Fig. 2, which is a side elevation of a chair provided with one form of my new seat, the back-frame being broken off. Fig. 3 is a bottom plan of my new chair-seat with its supporting-frame sectioned on line 3 of Fig. 4, which is a view partly in section on line 4 4 of Fig. 3. Fig. 5 shows another form of my chair-seat.

My invention relates particularly to the art of making the so-called "rattan furniture," and is a chair-seat which has a dependent border of rattan, strands of cane, or the like, the border being formed by combining pieces of rattan or the like with stakes, which are inserted in holes on the upper side of the chair-frame and are then bent outwardly and downwardly, as more fully explained below.

It is well known to all skilled in the art that it is practically essential that pieces of rattan furniture should have a light and graceful appearance, and that this requirement renders it exceedingly difficult to make the pieces strong and durable, because braces of requisite number and size to give the desired stiffness and strength to the piece render the piece clumsy and ungraceful in appearance.

The object of my invention is to enable rattan-chair makers to produce a chair which has a light and graceful appearance, but which at the same time has a strong well-braced supporting-frame, and my chair-seat, which is capable of use with supporting-frames and backs of various styles, is consequently provided with the dependent border of novel construction to hide the main braces of the supporting-frame from view.

In the drawings, A is the seat, A' the supporting-frame, and A² the back. Frame a of seat A is bored to receive the ends of legs a',

which, with the dowels a² and braces a³, make up the supporting-frame A'.

In order to hide from view the braces a³ and dowels a², upon which I usually wholly rely for making the supporting-frame stiff and durable, I provide the seat with the dependent border B, of wicker or strand work, which is made up of pieces, b, of rattan secured in holes a⁴ in frame a, and other pieces, b', of rattan interwoven with the pieces b. The holes a⁴ do not, preferably, extend entirely through the frame a; but whether they do or not the pieces b (commonly called "stakes") are inserted in holes a⁴ from the upper side of the seat, and are then bent outwardly and downwardly. This gives the chair-seat a graceful and luxurious appearance. The free ends of pieces b are confined in a finishing, b², and the border B is made wide enough to hide the main braces of the supporting-frame, which are heavy and strong, and yet do not prevent the chair from having a light and graceful appearance.

The back A² is secured to the seat A in a way too well known to require description.

It is obvious that the border B may be made either rounded or flat, just as desired. If the border is to be rounding, as I prefer it should be, the pieces b, being inserted in holes a⁴ in frame a, are bent downwardly and outwardly and then inwardly, their other ends being secured in a finishing, as shown, or to a supplementary frame, or carried back to frame a, as will be readily understood without further explanation by all skilled in the art. Pieces b are preferably glued in holes a⁴. Of course other pieces than b² may be interwoven or otherwise combined with pieces b, and the border may be made in many different styles.

It is plain that the pieces b' are readily bent so as to form a flange projecting above the upper support of the seat, if desired to hold a cushion in place, (see Fig. 3;) or the frame may be cut away, as shown in Fig. 5, to prevent the bent pieces b from projecting above the upper surface of the seat.

I am aware of Hopkins's patent, No. 69,808, dated October 15, 1867, Mabbett's patent, No. 172,136, dated January 11, 1876, and Ellis's

patent, No. 257,439, dated May 2, 1882, and disclaim all that is shown in them.

What I claim is—

The improved chair-seat herein described, 5 whose frame *a* is provided with a dependent border, *B*, formed of pieces *b*, secured in holes *a'* of frame *a*, and other pieces, *b'*, combined with pieces *b*, the pieces *b* being bent outwardly

and downwardly from the upper side of the frame *a*, all substantially as and for the purpose set forth.

BENJAMIN J. BUCKMAN.
